UNITED STATES PATENT OFFICE.

HENRY H. FREUND, OF WEEHAWKEN, NEW JERSEY.

PRESS FOR SEALING TUBE ENDS.

1,237,630.

Specification of Letters Patent. Patented Aug. 21, 1917.

Application filed March 24, 1917. Serial No. 157,077.

To all whom it may concern:

Be it known that I, HENRY H. FREUND, a citizen of the United States of America, residing at Weehawken, Hudson county, State 5 of New Jersey, have invented certain new and useful Improvements in Presses for Sealing Tube Ends, of which the following is a full, clear, and exact description.

This invention relates to improvements in 10 collapsible tube-end sealing devices, or in other words, in presses provided with dies to affix seals to such tubes. My improved device is arranged to affix seals to the ends of collapsible tubes such, for instance, as are 15 used to contain tooth or shaving-paste, said seals consisting of channeled strips that are slipped over the ends of the tubes. The seals, when placed upon the tubes, will be somewhat loose, but my improved device is 20 arranged to cause a portion of the seals to interlock with a portion of the tube. My improved device is also arranged to place record indications upon the seals, the said indications acting as a supplemental seal, as 25 will hereinafter be explained.

I will now proceed to describe my invention in detail, the novel features of which I will point out in the appended claims, reference being had to the accompanying drawings, forming part hereof, wherein:—

Figure 1 is a side elevation of an embodiment of my invention;

Fig. 2 is an enlarged plan view of the end of the support which carries one of the dies;

Fig. 3 is an enlarged bottom plan view of the end of the movable carrier which supports the other die;

Fig. 4 is an enlarged end view of the assembled carrier and support together with 40 the dies carried thereby;

Fig. 5 is an enlarged perspective view of the upper die;

Fig. 6 is an enlarged perspective view of a portion of a collapsible tube and a seal 45 applied thereto;

Fig. 7 is a similar view illustrating the appearance of the seal after having been acted upon by the dies.

Fig. 8 is an enlarged sectional view, the 50 section being taken on a line 8—8 in Fig. 7; and

Fig. 9 is an enlarged perspective view of the seal.

As herein indicated, my improved end 55 sealing device or press consists of a support 10 having upstanding ears 11, 11, to which

a carrier 12 is pivotally secured by a pin 13 which passes through the ears 11 and hub 14 of the carrier. The carrier 12 is in this instance embodied in the form of a lever 60 which is acted upon by an eccentric cam 15 carried by a shaft 16 journaled in the ears 17 carried by the support 10. To rock the carrier or lever 12 upon its pivot pin 13, I employ a suitable power device (not shown) 65 which operates a sprocket chain 18 which passes around a sprocket wheel 19 carried by a shaft 20. The shaft 20 also carries another sprocket 21 which, by means of a chain 22, drives the shaft 16, upon which the cam 70 15 is mounted, by means of a sprocket-wheel 23 carried by said shaft 16.

The sealing devices proper consist of dies 24 and 25 carried by the support 10 and carrier 12 respectively. The die 24 is fixed 75 to the support 10 by screws 26, while the die 25 is removably secured to the carrier 12 by a clamp 26. The clamp 26 consists of a bar pivotally secured to the carrier 12, at one end thereof, by a screw 27, the other end of 80 said clamp being provided with a recess or jaw 28 to receive a locking-screw 28^a carried by the support 12. The upper die 25 is set in a pocket 29^a carried by the carrier 12 and the clamp 26 passes over the die held in 85 said pocket. When the locking screw 28^a is screwed down tightly against said clamp, the die 25 will be held securely in place.

A further feature of my invention consists in providing supplemental impression 90 devices which in this instance consist of type 29 carried by the die 25. To retain the type 29, I provide the die 25 with a recess or pocket 30 into which the type are placed, said type being held in said recess by the 95 clamp 26. The clamp 26 performs two functions,—that of holding the die 25 in place and also that of holding the type in place in said die.

The type 29 are arranged to represent a 100 certain identification, for instance, the serial number of a certain lot of goods, or any other private identification. I also preferably provide the lower die 24 with fixed type or impression devices 31 and 32 indicating 105 A and B respectively. The letters A and B represent preferably the name of the manufacturer.

The type 29 and also the impression devices 31 and 32 are arranged to form 110 impressions in the seals deep enough to cause said impressions to interlock with the mate-

rial of the tubes for a purpose to be hereinafter explained.

To produce a perfect seal, I provide the die 25 with elongated projections 33 at each end thereof, and the die 24 with elongated depressions 34 at each end thereof, to aline with the projections on the die 25.

The seals consist of channeled strips 35 of relatively thin material which are previously formed and slipped on to the ends 10 of the tubes 37. After the seals have been placed on to the tubes, the ends of the tubes are placed between the dies 24 and 25, the press being of course in operation, a 15 guide 37 being provided to aline the ends of the tubes with the dies.

When the dies come together they will crush the seal and end of tube therebetween together, but unless some interlocking 20 effect is produced, the tubes will be liable to leak and the seals liable to come off.

To prevent the seals from coming off, and also to prevent leakage, I interlock the seals and tubes. To interlock the seals and tubes 25 is the function of the projections 33, on the upper die, and the depressions 34 in the lower die. When the dies come together, the projections 33 will force a portion of the seals and a portion of the tubes toward the 30 depressions 34 in the lower die. The impression type 29 and impression devices 31 and 32 will also force their corresponding portions of the seals inwardly to interlock with the material of the tubes. After a tube has 35 been withdrawn from the press, it will appear as shown in Figs. 7 and 8. After a seal has been acted upon by the dies, the said seal will be interlocked with the tube and cannot be withdrawn. The interlocking of 40 the seals and tubes both by the projections and depressions of the dies and also by the type 29 and impression devices or type 31 and 32, effectively produce a leak-proof seal.

To regulate the movement of the carrier 12, I provide an adjustable screw 38 which acts 45 upon a plate 39 which in turn rests upon the cam 15. The opening between the dies 24 and 25 can be increased or decreased by regulating the screw 38.

What I claim as my invention is:

1. In a device of the kind described, in combination, a support, a die carrier movably mounted thereupon, said carrier having a front flat side formed with a rectangular socket, a rectangular die fitting snugly 55 in said socket flush with the outer side of said carrier, said die being formed centrally with a rectangular recess, a plurality of interchangeable dies fitting said recess and frictionally engaging one another, and a 60 clamping bar engaging the flat side of said carrier and adapted to bear against said rectangular die as well as against said interchangeable dies, all of said dies having impression-making projections. 65

2. In a device of the kind described, in combination, a support, a carrier movably carried thereupon, a fixed die carried by said support, said carrier having a socket, a die fitting said socket and having a transverse 70 recess, a plurality of type fitting in said recess, a pair of depending impression-making projections formed at the opposite ends of said die, said first-named die having cavities at the opposite ends of its upper side 75 adapted to receive said impression-making projections, and unitary means for simultaneously clamping said second-named die and said first-named type within said carrier. 80

Signed at New York city, N. Y., this 21 day of March, 1917.

HENRY H. FREUND.
